UNITED STATES PATENT OFFICE

EDUARD OTTO ZWIETUSCH, OF VIENNA, AUSTRIA, ASSIGNOR TO INTERNATIONAL STANDARD ELECTRIC CORPORATION, OF NEW YORK, N. Y.

AUTOMATIC SWITCHING APPARATUS

Application filed December 12, 1930, Serial No. 501,897, and in Austria December 24, 1929.

This invention relates to automatic switching apparatus and more particularly to two-motion automatic switches such as are used in automatic telephone systems.

5 The object of the invention is to provide an improved and simplified form of such a two-motion automatic switch, which shows a very compact structure, while its efficiency and functions are fully maintained.

10 According to one feature of the invention a two motion switch is provided in which both longitudinal and rotary motion of the wipers are effected by a member which is driven in one only of said directions by means of an operating magnet, and in which the change-over from one direction to the other is effected by a clutch device associated with said member, and in which the said clutch device is directly controlled by an auxiliary 15 armature of the said operating magnet.

According to another feature of the invention a selector switch is provided having two selective motions one of which serves to move the movable contact organ or organs to a particular row of fixed bank contacts, whilst the other serves to move said organ or organs to a particular contact or set of contacts of said row, and in which the said organ or organs are mounted on a carriage 20 comprising a rack adapted to cooperate in such a manner with a rotatable drum having a plurality of helical teeth that upon a relative movement of the rack and the drum during the rotation of the latter part, the carriage is caused to perform one of the two selective motions.

According to another feature of the invention the operating magnet is provided with an auxiliary armature which is made slow 25 acting whereby it fails to follow the impulses which actuate the main armature to operate the switch, said auxiliary armature co-operating with the clutch device to control the latter between trains of impulses.

According to a further feature said member takes the form of a spiral toothed rotary drum which co-operates with a rack on a wiper carrying element in such a manner as to effect longitudinal movement thereof.

According to still another feature the said

clutch device takes the form of a lever pivoted on the rotary brush carriage guide and arranged to cooperate with a series of stops on the rotary drum whereby the brush carriage may be locked for movement with said drum, the movement of said lever for engaging the said stops being controlled by the auxiliary armature of the operating magnet. 55

It is believed that a complete understanding of the invention will be had from the following description taken in conjunction with the drawings in which:—

Fig. 1 is a side-view of the selector mechanism.

Fig. 2 gives a top view of the selector including a portion of the contact bank.

Fig. 3 is a sectional side elevation of a portion of the selector mechanism.

Fig. 4 is a sectional view of the selector mechanism taken at right angles to Fig. 3 and showing at *a*, *b* and *c*, a detail in various positions. 75

Fig. 5 is a sectional plan view of a portion of the mechanism shown in Figs. 3 and 4.

Fig. 6 is a side view of a portion of the drum 5 showing at *a*, *b* and *c* various positions of the locking device. 76

Fig. 7 is a perspective view of an electromagnet, suitable for the selector according to this invention. 80

Figs. 8, 9 and 10 are respectively plan, side elevation and end elevation views of the electromagnet.

The principal parts of the selector will first be briefly described and their interrelation and operation will be described more in detail hereafter. The reference 26 designates the main frame of the selector, 1 is the electromagnet supported thereby and having two armatures 2 and 13 respectively of which 2 is a fast armature capable of responding to impulses, whereas 13 is a slow releasing armature which fails to respond to impulses but operates at the commencement of each train of impulses and releases at the end thereof to perform a change-over operation from vertical to rotary movement of the brushes. 14 is a sub-frame rotatably mounted on a spindle 21 on the main frame and comprising a vertical slide in which the brush 95

carriage 7 is slidably mounted. 5 is a toothed drum rotatably mounted on the spindle 21 and adapted to be driven by the pawl and ratchet gear 3, 4 from the fast armature 2, the teeth 6 on the drum cooperating with the rack 8 on the brush carriage 7 to impart vertical motion to the brush carriage when the sub-frame 14 is held against rotation. 9 is the return spring for the drum 5. 14b is a bracket secured to the sub-frame 14 and having pivotally supported in it on the pin 14c a pawl or locking device 11 which on the one hand cooperates with an extension 13a of the slow armature 13 and on the other cooperates with teeth cut on the lower periphery of the drum 5. This pawl 11 therefore constitutes a clutch device by which the drum 5 is operatively connected with the sub-frame 14 for rotation of the brush carriage 7 thereby. 16 is a ratchet wheel fixed on the stationary spindle 21 and with which cooperates the spring pawl 15 on the sub-frame 14 whereby the sub-frame is retained in position against the action of the return spring 9. A pin 19 on the drum 5 cooperates with the pawl 15 to release it from the ratchet wheel 16 on the return motion of the selector. A pin 18 on the sub-frame 14 serves to tension the leaf-spring 17 during setting of the selector and when released this spring serves to reset the pawl 11 all as hereinafter fully described.

Referring first to Figs. 1 and 2 which show the inter-relation of the parts of the selector it will be seen that the selector comprises a frame 26 to which is attached the contact arc 23 and the electromagnet 1 with its two armatures 2 and 13 (the electromagnet and its two armatures will be described later).

The armature 2 carries at one end a driving pawl 3 engaging a ratchet gear 4. This gear is rigidly connected with a drum 5 arranged rotatably on a stationary shaft 21. The drum 5 has on its outside a plurality of helical threads or helical gear teeth 6 respectively, whereas inside, the drum is recessed so as to receive a spiral spring 9 (see Figs. 3 and 4) one end of which is fastened to the stationary shaft 21, whereas the other end is fastened to the drum. The multiple spiral thread 6 engages a rack 8 which is rigidly connected with the brush carriage 7. The spring 9 tends to rotate the drum 5 in such a direction that, through the medium of the retaining pawl 11 and the stop 12 the lug 14a on the slide 14 is pressed against the frame 26. The edge of the drum 5 is provided with a suitable number of specially formed teeth (see Fig. 6). The retaining pawl 11 which is mounted rotatably on the slide 14 for the brush carriage 7 is arranged to coact with said teeth. Due to the action of the spring 22, the retaining pawl tends to engage with the teeth of the drum 5 entirely, but is prevented from doing so, when the selector is in its normal posi-

tion, by means of the stop 12 arranged on the drum 5 (Fig. 1 and Fig. 6) and is held in the position shown at "a" of Fig. 6.

The brush carriage 7 carries the contact brushes 24 which make contact with the contacts 25 of the contact arc, 23 but are out of contact with them when in the normal position. The shaft 21 is also rigidly connected with a ratchet gear 16 which engages with the pawl 15 when the slide 14 rotates. This latter slide in which the brush carriage glides is likewise arranged to rotate about the shaft 21. In the initial position of the selector the pawl 15 is prevented from engaging the gear 16 by the pin 19 mounted on the drum 5. Likewise in the initial position of the selector the spring stop 20 locks the slide 14 against rotation by the pawl 11. The slide 14 also carries a projection 18 which during the rotation of the slide 14 tensions the spring 17 and releases it later on (as explained when describing the method of operating).

When the selector is used either as group selector or as a connector, its operation is as follows:

The incoming impulses cause magnet 1 to attract its armatures 2 and 13. Whereas the armature 13 is made to release slowly by suitable means (to be described later) and consequently does not follow the impulses, the armature 2 follows the impulses and rotates by means of the driving pawl 3, the gear 4 and the drum 5 connected with same. Depending upon the extent to which the brush slide is to be lifted, the multiple threads of the helix 6 of the drum 5 consecutively engage the teeth of the rack 8 and thus lift the contact brushes 24 corresponding to the number of the first series of impulses. During this operation the brush carriage 7 slides in the slide 14. After the first vertical step of the selector, the pawl 11 slides from position "a" (Fig. 6) to position "b" and is prevented by the arm 13a on the attracted armature 13 from completely engaging with the teeth of drum 6 as shown at "c" in Fig. 6. During these impulses causing the elevation of the brushes the locking part acts as a retaining pawl and thereby prevents the drum 5 from making a return movement.

The interval between the first and second series of impulses causes both armatures 2 and 13 of the magnet 1 to release, the latter releasing the locking device 11 (as shown at "c" Fig. 4) which is now free to perfectly engage the teeth of the drum 5 and assumes the position shown at "c" in Fig. 6. This brings about the rigid coupling between the slide 14 and the drum 5, bearing the ratchet gear 4. At the same time the lower end of the locking device 11 disengages the spring stop 20 which thus far prevented it from rotation. The selector, however, is held stationary by the action of the spiral spring 9 pressing the lug 14a against the frame 26 and does not rotate

until a new series of impulses operates the magnet.

This new series of impulses causes the magnet 1 to again attract both its armatures. 5 Each impulse as described above, acts on the ratchet gear 4 through magnet 1, armature 2 and driving pawl 3. But owing to the rigid coupling between the slide 14 and the drum 5 both will rotate and with them also the brush 10 carriage 7, until the brushes have reached the terminal of the contact arc corresponding to this series of impulses. The pawl 15 locks the drum by engaging the stationary gear 16. The armature 13 has no effect, since the lower 15 portion of the locking device has been removed from its reach.

At the end of the conversation the rotation described above is continued by suitable means until the brush 24 has passed the last 20 terminal of the arc. During this period the pin 18 has tensioned the spring 17 which is immediately released when the brushes no longer engage the contacts. The spring 17 is so shaped as to be released by the bolt 18 25 when the last terminal has been reached. The spring then strikes the locking device 11 removing the latter from the teeth of the drum 5. This unlocks the coupling between the slide 14 and the drum 5. The drum 5 is now 30 free to rotate backward under the action of the spiral spring, thus returning the set of brushes downward into its initial level. The return motion of drum 5 continues until the stop 12 on the drum 5 reaches pawl 11. At 35 the same moment the pin 19 reaches the pawl 15, lifts it from the ratchet 16, thus releasing the lock against a return movement of the slide 14 which under the action of the spring 9 returns to its initial position in which the 40 pawl 11 engages the spring stop 20, and the selector is again in its initial position.

The selector may be equipped with the requisite sets of supplementary spring contacts which may operate at various positions 45 and in various circuits. They are not shown, because they are not a feature of the invention.

The contact brushes may be connected in the usual manner. 50 Referring now to Figs. 7 to 10 which illustrate a suitable construction of electromagnet for the selector, it will be seen that the electromagnet comprises two flat cores 101 carrying the coils 102. The two cores are 55 mounted on a common support 103 (Fig. 8). At one end both coils extend beyond the cores and these extended coil ends receive a U-shaped armature 4 which is drawn into the coils. The armature is pivoted on the 60 shaft 5 and its prolongation carries the driving pawl. Due to the two-core construction of the electromagnet a double air-gap causes the magnet lines of force to disappear rapidly, so that the armature will operate 65 quickly. The armature 4 is the equivalent

of the armature 2 in Figs. 1 and 2. At the opposite end the two cores are slotted, so that each core is divided and has two subdivisions. One of these subdivisions on each core is provided with copper blocks 6, whereas the opposite core subdivisions are not provided with such blocks. Therefore, if the current is closed or interrupted, a phase displacement with respect to the originating and disappearing magnetism will occur in the pairs of subdivisions provided with copper blocks as against the other pair of subdivisions. This phase displacement is effective when the armature 7 which is rotatable around the shaft 8 is attracted and operates to retard the release of the armature when the current is interrupted. It therefore does not release until a series of current interruptions ceases. This armature 7 is the equivalent of the armature 13 of Figs. 1 and 2. At one end the retarded armature is provided with a stop which in connection with the selector performs various operations as referred to in the description and as shown in Fig. 4 at *a*, *b* and *c*.

What is claimed is:

1. A two-motion selector switch comprising in combination an electro-magnet, a member which is driven in one direction by said electro-magnet, means whereby both longitudinal and rotary motion of the switch wipers are effected by said member and means whereby the change over from one direction to the other is effected between trains of impulses. 100

2. A two-motion selector switch comprising in combination an electro-magnet, a member which is driven in one direction by said electro-magnet, means whereby both longitudinal and rotary motion of the switch wipers are effected by said member, and means controlled by an auxiliary armature of said electro-magnet whereby the change over from one direction to the other is effected. 105

3. A two-motion selector switch comprising in combination an electro-magnet having two armatures, a member which is driven in one direction by one of said armatures, means whereby both longitudinal and rotary motion of the switch wipers are effected by said member, and means under the control of the other armature for effecting the change over from one direction to the other. 110

4. A two-motion selector switch comprising in combination an electro-magnet having two armatures, a member which is driven in one direction by one of said armatures, means whereby both longitudinal and rotary motion of the switch wipers are effected by said member, and a clutch device associated 120 with said member and adapted to be controlled by the other armature of said electro-magnet to effect the change over from one direction to the other. 125

5. A two-motion selector switch comprising

- ing in combination an electro-magnet having two armatures, a member which is driven in one direction by one of said armatures, means whereby both longitudinal and rotary motion of the switch wipers are effected by said member, and means under the control of the other armature for effecting the change over from one direction to the other, said other armature being slow acting whereby it fails to follow the impulses which actuate the first mentioned armature.
6. A two-motion selector switch comprising in combination an electro-magnet, a toothed drum adapted to be rotated by said electro-magnet, a longitudinally movable wiper carrying member operatively connected with said toothed drum and adapted to be moved in the longitudinal direction thereby and means under control of said electro-magnet to connect said wiper carrying member with said toothed drum for rotation thereby.
7. A two-motion selector switch comprising in combination a frame, an electro-magnet mounted on said frame, a toothed drum rotatably mounted on said frame and adapted to be rotated by an armature of said electro-magnet, a sub-frame comprising a slide rotatably mounted on said frame, a wiper carriage slidably mounted in said slide and having a rack engaging said toothed drum and selective means whereby rotation of said drum is effective to move the wiper carriage in said slide and to rotate said sub-frame.
8. A two-motion selector switch comprising in combination a frame, an electro-magnet mounted on said frame, a toothed drum rotatably mounted on said frame and adapted to be rotated by a pawl and ratchet gear operated by an armature of said electro-magnet, a sub-frame comprising a slide rotatably mounted on said frame, a wiper carriage slidably mounted in said slide and having a rack engaging said toothed drum, a plurality of stops on said drum and a clutch member pivoted on said sub-frame and adapted to engage said stops to clutch said sub-frame to said drum for rotation thereby.
9. A two-motion selector switch comprising in combination a frame, an electro-magnet mounted on said frame, a toothed drum rotatably mounted on said frame and adapted to be rotated by a pawl and ratchet gear operated by an armature of said electro-magnet, a sub-frame comprising a slide rotatably mounted on said frame, a wiper carriage slidably mounted in said slide and having a rack engaging said toothed drum, a plurality of stops on said drum, a clutch member pivoted on said sub-frame and adapted to engage said stops to clutch said sub-frame to said drum for rotation thereby and means controlled by an auxiliary armature of said electro-magnet for controlling movement of said clutch member.
10. A two-motion selector switch comprising in combination a frame, an electro-magnet mounted on said frame, said electro-magnet having a main armature which is quick acting and adapted to be operated in accordance with trains of current impulses transmitted to said electro-magnet and an auxiliary armature which is slow to release and adapted to remain operated through such trains of current impulses, a toothed drum rotatably mounted on said frame and adapted to be rotated by said main armature, a sub-frame comprising a slide rotatably mounted on said frame, a wiper carriage slidably mounted in said slide and having a rack engaging said toothed drum, a plurality of slots in said drum, a clutch member pivoted on said sub-frame and adapted to engage said slots, a lever operatively connected with said auxiliary armature and adapted to prevent engagement of said clutch member with said slots during a first train of impulses and a stop member adapted to engage said clutch member to prevent rotation of the sub-frame when said clutch member is out of engagement with said slots.
11. A two-motion selector switch comprising in combination a frame, an electro-magnet mounted on said frame, said electro-magnet having a main armature which is quick acting and adapted to be operated in accordance with trains of current impulses transmitted to said electro-magnet and an auxiliary armature which is slow to release and adapted to remain operated through such trains of current impulses, a toothed drum rotatably mounted on said frame and adapted to be rotated by said main armature, a return spring for said drum, a sub-frame comprising a slide rotatably mounted on said frame, a wiper carriage slidably mounted in said slide and having a rack engaging said toothed drum, a plurality of slots in said drum, a clutch member pivoted on said sub-frame and adapted to engage said slots, a lever operatively connected with said auxiliary armature and adapted to prevent engagement of said clutch member with said slots during a first train of impulses, a stop member adapted to engage said clutch member to prevent rotation of the sub-frame when said clutch member is out of engagement with said slots and means operated during the setting motion of the switch to effect its return to normal.
12. A two-motion selector switch as claimed in claim 11 in which the clutch member is under the control of a spring which normally tends to move said clutch member into engagement with the slots in the drum and in which a spring member tensioned during rotation of the drum is adapted to cooperate with said clutch member to force the latter out of engagement with said slots at the end

of the rotary movement of the drum in one direction, to allow said drum to return to normal position under the influence of said return spring.

5 13. A two-motion selector switch comprising in combination an electro-magnet, a member which is adapted to be driven in one direction by said electro-magnet, a return spring for said member, means whereby both 10 longitudinal and rotary motion of the switch wipers are effected by said member, a clutch device adapted to effect the change over from one direction to the other, and means operated during the movement of said member to effect the return of the switch wipers to normal position.

In witness whereof I hereunto subscribe my name this 24th day of November 1930.

EDUARD OTTO ZWIETUSCH.
